231,255

REFUSE COMPACTOR

Joseph F. Longo, Wilton, Conn., assignor to International
Dynetics Corporation, South Norwalk, Conn.

Filed Mar. 29, 1972, Ser. No. 239,406

Term of patent 14 years

Int. Cl. D15—09

U.S. Cl. D55—1 B

FIG. 1

FIG. 2

FIG. 1 is a front perspective view of the refuse compactor according to the present invention.

FIG. 2 is a rear perspective view of the refuse compactor in which the container has been removed.

I claim:

The ornamental design for a refuse compactor, substantially as shown and described.

References Cited

UNITED STATES PATENTS

D. 205,164 6/1966 Bryant ----- D55—1 B
3,654,855 4/1972 Longo ----- 100—229 A

WALLACE R. BURKE, Primary Examiner

A. P. DOUGLAS, Assistant Examiner